50 and diameter 14 with sufficient fluid pressure to 55 spray the liquid in a fan-like pattern. At this point the liquid is directed to the back of the hand 15, leaving the fingers and thumb free so that a 60 person can manipulate a cloth or sponge for cleaning purposes. The device is secured to the hand by a strap 10 which is passed around the hand and 65 secured to itself. The strap 10 is made of a flexible material such as leather, cloth, or the like, and is provided 70 with a circular-shaped spray head 11 which is 75 secured to the strap 10. The spray head 11 is 80 provided with a coupling nipple 16 for hose fitting therewith, a portion of the hose being indicated at 85 17, which is the fluid supply conduit. The nipple 16 is 90 formed with a valve casing 18 having port communication 95 with the hose 17 or the nipple 16 and leading from this casing is a delivery tube 20 which opens 100 into the head 11 so that fluid from the hose 17 will flow into the head 11 and be discharged therefrom through the perforations 13 for spray purposes.

UNITED STATES PATENT OFFICE

2,209,861

SPRAY

Charles W. Torbert, Oklahoma City, Okla.

Application September 25, 1939, Serial No. 296,519

1 Claim. (Cl. 299—112)

The invention relates to a spray device and more especially to a hand sprayer, being refinements over the subject matter of United States Letters Patent No. 1,538,961, issued May 26, 1925.

5 The primary object of the invention is the provision of a spray device of this character wherein the same can be fitted to the hand of a person with the spray head at the palm of the hand, leaving the fingers and thumb free so that a 10 sponge, cloth or other article can be readily grasped for the use thereof and also to become saturated with fluid when issued from the head of the device and thus assuring a more thorough cleaning operation in the use of said device than 15 would have been the case if the sprayer were required to be manipulated by either one or another hand of a person independently of the manipulation of the sponge, cloth or other cleaning applicator.

20 Another object of the invention is the provision of a device of this character wherein the liquid flow is regulated in a convenient manner in that a trigger is located appropriately for manipulation by a finger or thumb of the hand of a person 25 when the device is worn upon the hand and in this manner a single hand is required for the wearing, the manipulation of and control of fluid flowing through the device leaving the other hand 30 of the operator free for any purpose required.

35 A further object of the invention is the provision of a device of this character wherein in the use thereof it will not mar or in any way damage a piece of work resultant from contact by the device and freedom of the hand wearing the device is assured, the device being applicable for spraying all kinds of fluids such as water, paint, 40 insecticide composition or for any purpose that such device is adaptable of performing, being especially adaptable for the cleaning of automobiles, including the windshield glass, door glass, et cetera.

45 A still further object of the invention is the provision of a device of this character, which is simple in its construction, thoroughly reliable and efficient in operation, enabling the wearing thereof by the hand of a person without discomfort, easy of operation, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed 55 out in the claim hereunto appended.

In the accompanying drawing:

Figure 1 is a fragmentary perspective view of the hand of a person showing the device constructed in accordance with the invention applied and in association with a sponge for the use 5 of said device for cleaning purposes.

Figure 2 is a rear elevation partly in section of the device.

Figure 3 is a sectional view taken on the line 3—3 of Figure 2 looking in the direction of the 10 arrows.

Figure 4 is a sectional view taken on the line 4—4 of Figure 2 looking in the direction of the arrows.

Similar reference characters indicate corresponding parts throughout the several views in the drawing.

Referring to the drawing in detail, the device constituting the present invention is a refinement over the subject matter of United States Letters Patent No. 1,538,961, issued May 26, 1925, and comprises a hand-embracing handle in the form of a strap-like loop 10 preferably made from strip metal and through which is passed the hand so that the said loop will underlie the palm of the hand and overlie the back thereof when the device is worn. This loop 10 has built medially of that portion underlying the palm of the hand, in this instance, a circular-shaped spray head 11, the strap being constructed to form the frontal portion 12 of this head 11 and said portion is perforated at 13 for fluid spray purposes. The back 14 of the head 11 is convexed to accommodate itself in the palm of the hand 15 of a person when such hand is engaged in the handle or loop 10 of the device as appearing in Figure 1 of the drawing.

Rising from the loop 10 at the upper stretch or portion overlying the back of the hand 15 is a coupling nipple 16 for hose fitting therewith, a portion of the hose being indicated at 17, which is the fluid supply conduit. The nipple is formed with a valve casing 18 having port communication 19 with the hose 17 or the nipple 16 and leading from this casing is a delivery tube 20 which opens 30 into the head 11 so that fluid from the hose 17 will flow into the head 11 and be discharged therefrom through the perforations 13 for spray purposes.

50 Interiorly of the valve casing 18 is a valve seat 21 for a plunger valve 22 which checks or regulates the flow of fluid through the device from the hose 17 to the head 11. The valve 22 is urged to seating position by a coiled spring 23 55

about said valve at its stem 24, the latter being cleared through a packing gland 25 and is adjustably connected at 26 to a manually operated trigger 27. The trigger 27 is pivoted at 28 in a bearing or bracket 29 on the loop 10. The trigger 27 is carried outwardly and downwardly at one end of the loop 10 exteriorly thereof so as to be conveniently confronted by the thumb or a finger of the hand 15 for manipulation thereby. 10 The device can be worn on the right or left hand of a person and when the right hand the thumb operates the trigger 27 and on the left hand the device is actuated by one of the fingers of the hand wearing the same.

15 When the loop 10 is upon the hand 15 with the head 11 palmed by said hand, the fingers as well as the thumb of the hand are free for grasping a sponge 30 or a cloth or other cleaning medium can be grasped for the use thereof by the hand 20 wearing the device.

Normally the valve 22 closes the flow of fluid through the device and by actuating the trigger 27 the flow of fluid will be had through the device 25 for the spraying of the fluid at the head 11 through the perforations 13.

The trigger 27 is formed with a fork 31 which straddles the stem 24 for engaging an adjustable abutment 32 upon said stem so that when the 30 trigger is depressed the valve 22 opens for the

flow of fluid from the hose 17 through the device and its spraying at the head 11.

What is claimed is:

A spraying device of the kind described comprising a straplike loop adapted to embrace a hand of a person so that a portion of the loop will underlie the palm of the hand and the upper portion overlie the back thereof, a spray head built with the strap medially of the lower portion thereof for fitting the palm of the hand, a hose coupling nipple built on said loop at the upper portion thereof and wholly outside of the same, a delivery tube communicative with the said nipple and the said spray head and having a curvature outwardly at substantially right angles to the loop whereby the said tube will be disposed between second and third fingers of the hand for the steadyng of the loop when embracing the hand, a valve controlling communication of the tube with the said nipple and disposed laterally to one side of the nipple, and a lever pivoted to the loop for disposition to one side thereof whereby the thumb of the hand will engage therewith and having operative connection with the valve for its control, the said lever at the thumb- 25 engaging end thereof being extended below the lowermost portion of the loop and further the said lever having a curvature corresponding to the loop formation at one end thereof.
